UNITED STATES PATENT OFFICE

LEON NOVAK, OF CLEVELAND, OHIO

EXERCISING DEVICE

Application filed November 3, 1928. Serial No. 317,052.

This invention relates to an exercising device particularly one that is intended to be used in gymnasiums, or in the home for development of the arm and back muscles. 5 Heretofore, apparatus employed for this purpose has usually taken the form of wall weights, which require considerable space to operate and are not easily adapted for home use. The principal object of the present invention is to provide a simple device which may be conveniently operated in a restricted space, without being permanently affixed to the wall or floor, and which may be cheaply made.

10 My invention, in the form illustrated, embodies a carriage having hand grips thereon, which extend laterally from the carriage and on opposite sides thereof. The exercise is obtained by the user assuming a kneeling position upon the floor with the carriage in front of him and hands resting upon the grips. The carriage is then pushed outwardly until the arms are extended and the chest is touching the floor. The movement 15 is completed by pulling the carriage backwardly until the original position is attained. To increase the muscular effort required to perform this movement, provision is made for effecting a braking action upon 20 the carriage movement either during the outward or inward motion.

In the drawings, Fig. 1 is a diagrammatic view of the carriage with the two extreme positions to be occupied during the exercise 25 movement; Figs. 2 and 3 are top and bottom plan views respectively of the device embodying my invention; Fig. 4 is a vertical longitudinal section through the device taken on a plane indicated by the line 4-4 40 of Fig. 2; Fig. 5 is a vertical section through the device taken on the plane indicated by the line 5-5 in Fig. 4; Fig. 6 is a perspective view of a bracket in which one of the wheels are intended to be mounted; Fig. 7 is 45 a bottom view of a modified form of casing construction; Fig. 8 is a longitudinal vertical section taken on the line 8-8 in Fig. 7 and Fig. 9 is a perspective view of one of the brackets used in the modified construction shown in Figs. 7 and 8.

The carriage is indicated as having a body portion 10 which in the form illustrated in Figs. 1 to 5 comprise a block of wood about ten inches in length and four inches in width at the mid-portion. Wheels 11 are journaled in the bottom portion adjacent the forward and rearward ends thereof. Hand grips 12 project laterally therefrom adjacent the mid-portion thereof.

A convenient manner of mounting each wheel in the body is to utilize a bracket indicated in general at 15. As illustrated, each bracket has a pair of depending arms 16 and a connecting cross piece 17. The brackets are mounted within cavities 20 in the body portion, and are intended in the present form to be capable of movement within the cavities with reference to the body. The function of such movement is to increase the resistance to the muscular effort required to move the device in a predetermined direction.

My exercising device is capable of use without the utilization of means for varying the resistance to movement, but inasmuch as 55 the muscular development resulting from any exercise is dependent upon the resistance opposed to the muscular activity, it is desirable that provision be made for increasing the resistance to either the outward or inward motion, or both. One form of means for varying the resistance embodies the provision of a brake which is intended to act upon the wheels, during the exercise movement. Accordingly, I have shown each 60 bracket as being mounted upon pivot pins, which are shown as threaded members, 25. The extent of the pivotal movement is controlled by set screws 26 which are illustrated as extending through the top of the body, 65 and as engaging the cross bars on the respective brackets. Adjustment of the cross bar position, as shown in Fig. 4, is such that during the inward movement of the exercise the wheels are out of contact with 70 the body. Such movement is shown by the broken line arrow. During this inward movement the cross bars are out of contact with the set screws, and are kept out of contact therewith by reason of the fact that 75

the normal pulling action upon the hand grips tends to pull the body of the carriage ahead of the wheels, thus causing the brackets to turn about their pivotal connections.

5 On the outward movement, reverse action takes place, and the cross pieces are forced against the ends of the set screws as indicated by the broken lines 17a in Fig. 4. The adjustment of the set screws is such that the 10 wheels are permitted to engage part of the body, which then acts as a brake to resist turning movement of the wheels. The degree of such resistance can be varied to suit the individual requirements of the user.

15 In Figs. 7 and 8, I have illustrated a modified form of casing construction as comprising a one-piece body member 30, having hand grips 31 extending laterally therefrom adjacent the mid portion thereof. Recesses 32 are shown adjacent each end of the body portion in which wheels 33 partially extend. The wheel supporting brackets, indicated in general at 34, are similar to those heretofore described. Springs 35 associated with the 20 set screws 36 function to urge the brackets to the position shown in Fig. 8. In use, the pressure of the operator forces the forward wheel against the partition 37, and the rearward wheel against the transverse end wall 38. This puts a braking action upon the 25 movement of the wheels. Upon the return stroke, the wheels are withdrawn from frictional engagement with the casing by the force of the springs.

30 35 An exercising device made in accordance with my invention is advantageous in that it permits performance of desired exercises without the necessity for expensive equipment, which is more or less permanent in nature, and which requires considerable wall and floor space. Moreover, my device is portable and can be readily carried from place to place. If desired, the exercise may be taken without the use of the brake, until 40 the muscles are developed to a point where additional resistance is desired. Thereupon the degree of resistance may be controlled in a very satisfactory and expeditious manner.

45 50 I claim:

1. An exercising device adapted to be pushed outwardly from and pulled inwardly toward the user, including a pair of wheels arranged in tandem relationship, a member connecting them, and hand grips extending laterally from the member in opposite directions and intermediate the wheels.

2. An exercising device adapted to be 55 60 pushed outwardly from and pulled inwardly toward the user, including a pair of wheels arranged in tandem relationship, a member connecting them, hand grips extending laterally from the member and intermediate the wheels, and means adapted

to be set and retained in various positions and operating independently of the hand grips for selectively varying the resistance to turning movement of the wheels.

3. An exercising device, comprising in 70 combination, a pair of wheels arranged in tandem relationship, a member connecting them, and means connecting the wheels to the member, including brackets mounted for pivotal movement in said member, and 75 means for limiting movement of the brackets with reference to the member when the member is moved in a predetermined direction.

4. An exercising device comprising in 80 combination a body having a hand grip, a bracket pivotally mounted in the body, a wheel carried by said bracket, means for adjusting the limit of pivotal movement of the bracket to provide a variable braking action between the wheel and means carried 85 by the body.

5. In an exercising device, the combination of a body, a pair of wheels carried thereby, hand grips for moving the body toward and from the user, and means for establishing a braking action on the wheels which acts for movement in one direction of the body and not in the other direction.

6. An exercising device, comprising in 90 combination a body, said body having a 95 plurality of recesses therein, brackets pivotally mounted within said recesses, wheels rotatably mounted on said brackets, springs 100 interposed between the body and brackets, for normally keeping the wheels out of contact with said body, but allowing contact when the body is moved in a predetermined direction, and settable means associated with the body and coacting with the brackets for preventing contact of the wheels with 105 said body when desired.

7. An exercising device, adapted to be pushed outwardly from and pulled inwardly toward the user, comprising a body formed of two members, a pair of hand 110 grips extending laterally from the top member in opposite directions, a pair of brackets mounted for pivotal movement in the bottom member, wheels carried by said brackets and means for limiting movement 115 of the brackets with reference to the body when the body is moved in a predetermined direction.

In testimony whereof, I hereunto affix my 120 signature.

LEON NOVAK.
